UNITED STATES PATENT OFFICE.

WILLIAM S. FAIRHURST, OF NEW YORK, N. Y.

DESIGN FOR A VALVE.

46,164.

Specification for Design.

Patented July 28, 1914.

Application filed June 4, 1913. Serial No. 771,771. Term of patent 14 years.

To all whom it may concern:

Be it known that I, WILLIAM S. FAIRHURST, a citizen of the United States, and resident of the borough of Brooklyn, in the city, county, and State of New York, have invented a new, original, and ornamental Design for a Valve, of which the following is a specification, reference being had to the accompanying drawing, forming part thereof.

Figure 1 is a face view of a valve illustrating my new design, and Fig. 2 is an edge view of the same.

I claim:

The ornamental design for a valve, as shown.

WILLIAM S. FAIRHURST.

Witnesses:

F. GEORGE BARRY,
CATHARINE S. SUNDGREN.
